CARL H. ROOT, OF DETROIT, MICHIGAN

AUTOMATIC AIR TEMPERATURE CONTROL

Application filed February 28, 1931. Serial No. 518,558.

This invention relates to thermostatic heat control for the air entering the carburetor of an internal combustion engine.

A primary object of the invention is to so construct a device of this character that it will furnish air to the carburetor at a temperature which gives the greatest efficiency to the motor.

Another object of the invention is to so construct such a device that a large area of heating surface will be in contact with the exhaust pipe and thereby warm the motor quickly in cold weather.

Still another object is to so construct such a device that it will be automatic in its operation, avoiding the necessity of the usual manual control.

In carrying out these objects, the invention is susceptible of a wide range of modification without departing from the spirit or sacrificing any of the advantages of the claimed invention; there being shown in the drawing for illustrative purposes a preferred and practical form, in which:

Figure 1 is a side elevation of a portion of an engine equipped with this improved temperature control;

Fig. 2 is a longitudinal section through the device constituting the invention;

Fig. 3 is a transverse section taken on the line 3—3 of Fig. 2; and

Fig. 4 is a similar view taken on the line 4—4 of Fig. 2.

In the embodiment illustrated the device constituting this invention comprises a cylindrical jacket 1 designed to encircle the exhaust pipe E of an internal combustion engine and made larger than said exhaust to permit the free circulation of air around the exhaust, between it and the jacket. This jacket 1 has an enlarged mouth 2 at its outer end through which cold air is designed to enter the jacket and be drawn into the jacket by the suction of motor. This jacket 1 may encircle the entire exhaust pipe or only a portion

thereof as may be desired and has extending laterally therefrom a pipe 2 through which hot air is designed to be conveyed to the carburetor air intake shown at A1 in Fig. 1 of the drawing, the carburetor being indicated at C.

A thermostat 10 is located within the pipe 2 and is here shown extended longitudinally thereof and includes a shaft or rod 11 which is journalled or supported in suitable spiders 3 and 4 located at suitably spaced intervals in the pipe 2. The shaft 11 has a small disk 12 fixed to the end thereof beyond the support 3 and is designed for a purpose presently to be described. The support 3 is fixedly mounted on a slidable sleeve 4 fitted within the pipe 2 and designed to be moved by the expansion and contraction of the thermostat 10 as will be presently hereinafter more fully described. This sleeve 4 operates as a valve 65 for bringing into and cutting off communication between the interior of the pipe 2 and the outer atmosphere. The tube 2 is provided with a plurality of openings 5 arranged circumferentially around the tube and over which the sleeve 4 is designed to slide to cover and uncover them according to the heat within the tube. Fixedly mounted in the tube 2 in rear of the thermostat and disk 12 carried thereby is an annular plate 6 through which the hot air from pipe 1 is designed to pass and the opening in which shown at 7 is covered or uncovered by the disk 12 controlled by the thermostat 10.

A truncated cone-shaped deflector 8 is mounted on the outside of the pipe 2 around the openings 5 therein and secured in any suitable manner with its flared mouth facing outwardly. This deflector is designed to protect the openings 5 against entrance of dirt and other elements.

In the use of this device it being installed as shown in Fig. 1, the suction from the engine will draw the air in through the pipes 1 and 2 and through the air intake pipe A1 to

the carbureter and from thence to the engine. The heat from the exhaust E will heat the air passing through these pipes and when the passing air becomes heated to a predetermined point the thermostat 10 will expand moving the disk 12 over the opening 7 in the partition 6 cutting off the entrance of further air and opening the openings 5 by the removal of the sleeve or sliding valves 4 from over them.

When the air in tube 2 has become sufficiently cool by the entrance of the outside air through openings 5 the thermostat 10 will contract and thus uncover the opening 7 in the partition 6 and permit the heated air from beyond to continue passing through the tube to the carbureter.

It will thus be seen that the temperature of the air fed to the carbureter through the air intake thereof will be controlled automatically by means of the thermostat 10 and hence after the device has once been installed no further attention will be necessary.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. In the combination with the exhaust pipe of an internal combustion engine, an air heater associated with said pipe, a hot air pipe leading from said heater and connected with the air intake of a carbureter, the hot air pipe having a plurality of circumferentially disposed passages for placing the hot air pipe in communication with the atmosphere, a sleeve within the hot air pipe and movable over said openings, a spider secured to said sleeve, a second spider secured to the interior of the hot air pipe, a thermostat located within the hot air pipe and connected between the spiders for causing the sleeve to open or close the openings, a circular plate fitting the hot air pipe and provided with a passage, a disk movable by the thermostat for closing the passage when the passages in the hot air pipe have been opened by the sleeve.

2. A device of the class described comprising an air heater associated with the exhaust pipe of an internal combustion engine, a hot air pipe connected between the heater and the air intake of a carbureter and provided with passages connecting the hot air pipe directly with the atmosphere, an annular valve closing said openings, a thermostat in the hot air pipe and connected to the valve so that when the temperature of the air is increased sufficiently the thermostat will move the valve from the openings and permit atmospheric

air to enter the hot air pipe for conduction to the carbureter, a disc secured in the hot air pipe between the heater and the openings in the hot air pipe and located at a right angle to the axis of the hot air pipe, said disc having an opening to permit hot air from the heater to pass directly to the carbureter, a second valve movable axially of the hot air pipe connected to the thermostat and adapted to close the opening in the disc when the annular valve has been moved from the openings in the hot air pipe.
